UNITED STATES PATENT OFFICE.

FRANÇOIS X. BRODEUR, OF LYNN, MASSACHUSETTS, ASSIGNOR TO UNITED SHOE MACHINERY COMPANY, OF PATERSON, NEW JERSEY, A CORPORATION OF NEW JERSEY.

CLICKING-MACHINE.

1,161,023.

Specification of Letters Patent.

Patented Nov. 23, 1915.

Application filed April 18, 1910. Serial No. 556,168.

To all whom it may concern:

Be it known that I, FRANÇOIS X. BRODEUR, a citizen of the United States, residing at Lynn, in the county of Essex and State of Massachusetts, have invented certain Improvements in Clicking-Machines, of which the following description, in connection with the accompanying drawings, is a specification, like reference characters on the drawings indicating like parts in the several figures.

This invention relates to machines for cutting out thin sheet material, such as upper leather for boots and shoes, and particularly to machines of the type disclosed in United States Letters Patent to Arthur Bates, 921,503, granted May 11, 1909, machines of this type being known to the trade as clicking machines.

20 The principal use to which the clicking machine is put is to cut out the parts of boot or shoe uppers and when thus employed the operator usually desires to have within convenient reach several of the dies which 25 he will be called upon to use in cutting up the skin or side of leather in order that he may cut up the exposed portions of the skin with the least effort and to the best advantage. It will be understood that in cutting parts of boot and shoe uppers from a skin or from a side of leather care must be 30 taken in the selection of the parts of the skin which are to form the different parts of the shoe and that while some portions of 35 the skin are suited for a particular part of the shoe, adjacent portions of the skin may not be suited for the same part. In order, therefore, that the operator may cut up the stock to the best advantage, it is usually necessary for him to try different dies so that 40 he may avoid defects in the skin and may use up as much as possible of the skin in the region of the injured parts.

45 In employing clicking machines of the type disclosed in the above-mentioned patent, in which a presser member is arranged to swing about a vertical axis at one side of the bed into different operative positions over the bed, the operators have usually 50 placed the set of dies which they are using upon a table or shelf at one side of the bed. It will be seen, therefore, that when the operator is locating one of these dies upon 55 the portion of the skin adjacent to the side of the machine remote from the table or shelf

upon which the other dies are placed, these other dies will be out of convenient reach, and that if he finds the part of the skin upon which he is operating is more suited for the part of the shoe to be cut by one of the other dies he will have to step to one side in order to reach the desired die and thus will be compelled to waste both time and energy in cutting up the skin.

Another practice sometimes resorted to to 65 avoid the difficulty just mentioned is to place the other dies upon portions of the skin which will not be under the presser member during the pressing operation. This practice is objectionable, however, as it requires 70 frequent rehandling of the dies and there is danger of injuring the stock by inadvertently leaving one of the dies within the path of movement of the presser member during the pressing operation.

An object of this invention is to facilitate the handling of the dies, and thereby increase the capacity of the machine, by providing a support for the dies which is so constructed and arranged that the dies 80 which the operator is using will be within convenient reach of the operator when he is operating upon any part of the bed.

Another object of the invention is to provide a support for the dies by which they 85 may be carried to either side of the operator and which is so constructed and arranged that access may be had to the dies from either side of the support.

Another object of the invention is to provide a support for the dies which constitutes 90 part of the machine and upon which the dies may be placed without danger of injury to their cutting edges.

With the foregoing and other objects in 95 view, the invention is herein shown as embodied in a clicking machine of the type disclosed in the above-mentioned patent, and the die support is shown as constituting a part of the presser member of said machine, 100 being preferably arranged to form an upper face of the platen of said presser member.

In the accompanying drawing, the figure is a perspective view of the commercial clicking machine to which the invention is 105 shown as applied.

The machine comprises a base 2 upon which is supported a table 4 for the cutting block 6, said base also carrying an overhanging arm 8 in which the vertically re-

ciprocating post 10 has bearings, the post 10 carrying the presser member 12 which is arranged to swing about the vertical axis of the post into different operative relations 5 to the cutting bed 6 and to reciprocate with the post to force a die 14 through the stock 16 supported upon the cutting bed. Besides the die 14, two other dies, 18 and 20, are shown in the drawing, the die 14 being one of the quarter dies, the die 18 being the other quarter die and the die 20 being the vamp die for a given size of shoe. As above pointed out, the operator will so locate these various dies upon the stock for the successive cutting operations that the 10 parts of the stock best suited to the different parts of the shoe may be utilized and that the stock may be cut without waste. To enable him to have the dies 18 and 20 within 15 convenient reach when he is placing the die 14, so that if he desires he may determine in advance of the operation of cutting a blank with the die 14 whether or not there will be stock enough to furnish a blank for one of 20 the other dies adjacent to the part which is to form the blank for the die 14, or that he may determine whether the stock upon 25 which he is about to place the die 14 may not to better advantage form part of a blank 30 cut by one of the other dies, the presser member 12 is provided with a die supporting table 22 which, in the present embodiment of the invention, forms the upper face 35 of the platen 24 of the presser member.

In order that the operator may have access to the dies from either side of the presser member a brace 26 which keeps the presser member from springing during the 40 pressing operation is preferably so arranged that a free space is left between the upper surface of the platen 24 and said brace, the brace being preferably connected to the presser member at its end remote from the post. To strengthen the brace 26 it is 45 provided upon its under side for some distance

from the post with a rib 28. A cover 30 is provided for the die supporting table 22 to prevent dulling of the edges of the dies resting upon said table.

Having described my invention, what I claim as new and desire to secure by Letters Patent of the United States is:

1. In a machine of the class described, a cutting bed, a presser member arranged to swing over the face of the bed from one side to the other, a support for said presser member about the axis of which it swings, a brace connecting the support and approximately the outer end of the presser member leaving substantially the entire upper surface of said member uninterrupted, thereby providing a die supporting shelf accessible to the operator from any position in which he may stand, whatever the position of the presser member. 60

2. In a machine of the class described, a cutting bed, a presser member arranged to swing over the face of said bed from one side to the other about a vertical axis located at the rear of the bed, a post by which said presser member is supported and about the axis of which it swings, a brace connecting said post and approximately the end of said member remote from the post leaving substantially the entire upper surface of 70 said member uninterrupted, thereby providing a die supporting shelf accessible from either side of said presser member, said brace being so spaced from said die supporting shelf that the operator may conveniently 75 reach with his hands a die wherever located upon said shelf. 80

In testimony whereof I have signed my name to this specification in the presence of two subscribing witnesses.

FRANCOIS X. BRODEUR.
